UNITED STATES PATENT OFFICE.

THOMAS R. STONEBURNER, OF ALEXANDRIA, VIRGINIA.

PORTABLE SHIELD FOR SOLDIERS.

1,205,680.

Specification of Letters Patent. Patented Nov. 21, 1916.

Application filed March 30, 1916. Serial No. 87,745.

To all whom it may concern:

Be it known that I, THOMAS R. STONEBURNER, a citizen of the United States, residing at Route No. 2, Alexandria, in the county of Alexandria and State of Virginia, have invented certain new and useful Improvements in Portable Shields for Soldiers, of which the following is a specification.

This invention has for its object to provide a device adapted to be supported in protective position upon the body of the soldier in such manner that the soldier may charge without interference by the shield, may kneel to fire with the shield upon the ground, or may completely reverse the shield so as to protect the rear of the person during retreat.

Further objects and advantages of the invention will be set forth in the detailed description which now follows.

In the accompanying drawing Figure 1 is a perspective view of the shield supported in the position it occupies during an advance. Fig. 2 is a perspective view illustrating the shield resting upon the ground and serving as a protection to the soldier firing from behind it. Fig. 3 is a plan view of the shield and associated parts. Fig. 4 is a detail perspective view of the shield in folded position. Fig. 5 is a detail view of the fastening for the belt. Fig. 6 is a detail view of a swivel member hereinafter described, and Fig. 7 is a detail of a spring spacing element hereinafter described.

Like numerals designate corresponding parts in all of the figures of the drawing.

Referring to the drawing, it will be seen that my improved shield comprises a V shaped construction consisting of two parts, A and B, which are hingedly connected with each other at 5. Each of the parts A and B comprises wings 6 and 7 which are hingedly connected with each other at 8 so that the parts may be brought to the folded position illustrated in Fig. 4. The wings 6 are provided with staples or eyelets 8^a upon their inner sides, and the wings 7 are provided with staples or eyelets 9 upon their inner sides, said staples or eyelets 8^a being engaged by snap-hooks of conventional form indicated at 10. These snap-hooks are carried by a strap 11 which passes up over the shoulders and behind the neck of the wearer. This strap carries loops 12 and 13 adapted to be engaged by snap-hooks 14 upon breast strap 15 which extends

across the breast of the wearer. Rear straps 16 are provided with snap-hooks 17 and 18 at their opposite ends which are adapted for engagement respectively with the loops 13 and the staples or eyelets 9.

A belt 19 of steel is provided with a series of pockets 20 formed by the proper bending of a metal strip. These pockets serve to receive cartridges in the usual and well-known way and I prefer to make the strip of aluminum. A readily detachable fastening must be provided for the belt. Such a form of fastening is indicated at 21 in Figs. 3 and 5. The particular type of fastening employed forms no part of the invention, though I prefer to employ a snap fastening such as is commonly used upon gaiters and which comprises a hook 22 adapted to pass through a slot 23. The straps 11 and 16 prevent the shield from sagging forwardly or rearwardly, and to hold the shield in proper spaced relation to the person rigid rods 24 are pivotedly connected with eyes 25 of wings 7 and the opposite ends of these rods are connected by snap-hooks 26 with eyelets 27 carried by the belt. These rigid rods 24 are made in two parts, 24^a, 24^b. These two parts of the rigid rods are connected to each other by a pin 24^c, having heads 24^d. These form a swivel which permits the part 24^b to turn with relation to the part 24^a so that if it becomes necessary for the soldier to retreat he may swing the shield over to protect the rear of his person at which time the snap-hooks 18 of the straps 16 may be engaged with the eyes 8^a. The various straps may be provided with suitable adjusting loops 28.

The plates 6 and 7 are made of spring steel. I am aware of the fact that it has heretofore been proposed to provide metallic shields of the same general nature as those herein shown and described but I am not aware that it has ever been proposed to make such shields of spring steel so that they are caused to have a locally yielding action by virtue of which they serve to deflect a bullet. It is apparent that the V shape of the shield aids in deflecting a bullet and that this action is supplemented by having the shields made of such material that they locally yield. In other words, the mere making of the shield of spring steel will not result in the spring action aiding in the deflection of the bullet unless the shield is so shaped that the bullet strikes the shield at

an angle other than at right angle. It will, therefore, be seen that there is a distinct co-action between the shape of applicant's shield and the nature of the material of 5 which the shield is made. If desired the rear edges of the plates 7 may be curved outwardly as shown at 29 in Fig. 3, and carry a packing of raw cotton which prevents a deflected bullet from injuring soldiers in the 10 rear of the soldier who is actually protected by the shield.

While the shield in Fig. 1 is illustrated as covering the body of the soldier and leaving the head exposed, it is apparent that the 15 shield may be raised or lowered at will by the straps and that the parts may be so arranged as to protect more of the upper portion of the body than of the lower portion thereof. I prefer to employ in conjunction 20 with the shield herein shown and described, suitable protecting armor for the portion of the body which projects below the shield. The specified construction of this armor forms no part of the present invention, because I am well aware that armor worn directly upon the person has long been known. However, I prefer to employ in conjunction 25 with the shield herein shown and described, protecting armor such as is indicated by the 30 leggings 30 which are preferably of metal. It is to be understood that any suitable type of armor may be employed to protect those portions of the limbs of the user which project below the shield.

35 To render it possible for the soldier to fire

from behind the shield when the shield is resting upon the ground, a suitable port hole 31 is provided, and as many of these port holes may be provided as is desirable.

If desired springs 31 may be employed in 40 lieu of the rigid rods 24.

Having described my invention what I claim is:—

1. A device of the character described, comprising a belt, swivel rods attached to 45 said belt, a V shaped metallic shield, means for securing said shield to said swivel members and straps for supporting said shield from the shoulders of the wearer; said straps being detachable from their engagement 50 with the shield, and said shield being reversible upon said swivel members.

2. A bullet-proof shield made of spring steel throughout to render it locally yielding, said shield being shaped to present a convex front face and means for supporting 55 said shield from the shoulders.

3. A bullet-proof shield of V shape, made of spring steel to render it locally yielding in combination with means for supporting 60 said shield upon the person.

4. A bullet-proof shield of V shape, having its rear edges curved outwardly to provide elements for catching bullets deflected by the other portions of the shield and 65 shoulder straps secured to said shield for supporting the shield upon the person.

In testimony whereof I affix my signature.

THOMAS R. STONEBURNER.
